(57) **CLAIM**

We claim the ornamental design for a clothing care machine, as shown and described.

DESCRIPTION

FIG. 1 is a front perspective view of a clothing care machine showing our new design with the inner shelf portion fully folded;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a cross-sectional view thereof taken through line 8-8 of FIG. 2;

FIG. 9 is a front perspective view thereof shown with the inner shelf portion deployed halfway;

FIG. 10 is a front view thereof;

FIG. 11 is a cross-sectional view thereof taken through line 11-11 of FIG. 10;

FIG. 12 is a front perspective view thereof shown with the inner shelf portion fully deployed;

FIG. 13 is a front view thereof;

FIG. 14 is a cross-sectional view thereof taken through line 14-14 of FIG. 13;

FIG. 15 is an exploded front view of the clothing care machine shown in FIG. 13; and,

FIG. 16 is an enlarged front perspective view of the inner shelf portion shown separately from the article in which it is embodied.

The broken lines in the figures depict portions of the clothing care machine which form no part of the claimed design.
